UNITED STATES PATENT OFFICE.

FREDERICK L. McCULLOCH, OF TAMPA, FLORIDA, ASSIGNOR TO WATSON ELISAPH DORCHESTER, OF TAMPA, FLORIDA.

CARBURETER ATTACHMENT.

1,262,219.

Specification of Letters Patent.

Patented Apr. 9, 1918.

Application filed October 16, 1916. Serial No. 125,989.

To all whom it may concern:

Be it known that I, FREDERICK L. McCULLOCH, a citizen of the United States, residing at Tampa, in the county of Hillsboro 5 and State of Florida, have invented certain new and useful Improvements in Carbureter Attachments; and I do hereby declare the following to be a full, clear, and exact description of the invention, such as will enable others skilled in the art to which it 10 pertains to make and use the same.

The present invention relates to improvements in carbureter attachments, and more specifically consists in connecting a conduit 15 between the usual float chamber, or other fuel receiving chamber, of the carbureter and the intake of the engine so as to place the same in direct communication, whereby the float chamber will be placed under the 20 influence of the suction produced by the engine cylinders, and which suction, creating a partial vacuum in the float chamber, will induce a flow from the fuel tank, which may be placed at a lower level on the vehicle, as 25 at present generally done.

It is the primary aim and object of my invention to dispense with a separate and distinct vacuum tank with all its attendant 30 parts and connections, and to also eliminate the necessity of including pumps in the gasoline line in order to compel the fuel to flow from the main tank to the float chamber of the carbureter which is generally placed at an elevation over said tank.

Such added devices as vacuum tanks and 35 pumps increase the cost of manufacture and the complexity of the system, and are troublesome in the matter of correct adjustment; and, moreover, provide additional 40 chambers and pipes that may be clogged by foreign matter in the fuel.

By my improved attachment such added 45 devices are entirely dispensed with and the float chamber of the carbureter directly converted into a vacuum tank, serving at once as the fuel receiving chamber for the carbureter under the control of the usual float valve, and a vacuum chamber which will, when the float valve is opened, induce a 50 flow of the fuel from the main tank to said chamber.

Other objects of my invention consist in providing regulating means for maintaining the degree of partial vacuum in the float 55 chambers substantially constant, such means

broadly including an air valve which relieves the increased suction as the engine speed advances.

In the accompanying drawings forming a part of this application, and in which similar reference symbols indicate corresponding parts in the several views:

Figure 1 is a side elevational view of a vehicle shown partly broken away to illustrate my improved carbureter attachment as 65 applied thereto.

Fig. 2 is an enlarged front elevational view, partly in section, of the carbureter, with my improved attachment fitted thereto;

Fig. 3 is a side elevational view of the carbureter shown partly in section and with parts of the attachment also illustrated.

Referring more particularly to the drawings, in Fig. 1 is shown an automobile indicated generally at 1, and having a main fuel tank 2 illustrated as mounted on the rear thereof, but which obviously may be placed at any other location thereon.

This fuel tank 2 receives the gasoline or 80 other fuel, which may be poured through a filling neck which is closed by the usual cap having an air vent therein through which atmospheric pressure is admitted to the surface of the fuel therein. The tank may be 85 equipped with the usual devices which, however, form no part of the present invention and are therefore not here illustrated. The gasoline or other fuel, is conveyed from the tank 2 in any suitable manner, as by the tube 90 or pipe 3, one end of which extends through the top thereof and down within the interior of said tank, terminating in a boss at the bottom for the purpose of receiving all of the fuel therein.

Instead of this connection or tube 3 running to a vacuum tank, in accordance with the present invention it is placed at its other end in direct communication with the filter-screen and through the float valve with the 95 float chamber 4.

This float chamber 4 forms a part of the usual carbureter construction designated generally at 5, and which is shown in the present drawings as being the Stewart carbureter 100 at present in use on the Dodge Brothers motor car. It will be appreciated, however, that the invention is not limited to an application to this type of carbureter, but may be employed on other types with equally good 110

results. The carburetor construction forms no part of the present invention, and therefore only such portions thereof as are necessary to an accurate understanding of the present improvement are illustrated in detail.

Adjoining the float chamber 4 is the aspirating chamber having the usual devices therein for regulating the supply of gasoline 10 from the float chamber to the mixing chamber 6. With the aspirating tube communicates the air supply 7, which is formed by an extension of the carburetor shell 5. This extension or air inlet 7 is adapted to be closed 15 by a cover 8 having formed therein a concentric series of openings 9, which are preferably radially elongated as shown in the drawings. These openings 9 are adapted to place the extension 7 in communication with 20 the outside atmosphere.

A flaring mouth 10 is formed in one piece or attached to the interior of the cover 8 and projects within the extension 7, presenting a large area to be placed under the influence of the suction created by the action 25 of the pistons of the engine. The flaring mouth 10 and cover 8 may be secured in the extension 7 in any suitable manner, advantageously as shown in the drawings, wherein 30 the edge of said mouth 10 is formed with a notch 11, which is received through a lug 12 on the extension 7. After the device has been inserted the cover 8 is turned so that the notch 11 moves out of registry with the 35 lug 12, and the parts thereby become locked in place.

The cover 8 is provided on its exterior with a boss 13 forming a socket in which is fitted one arm of an elbow 14, to the other 40 end of which is connected a pipe or equivalent conduit 15, which has its opposite end coupled in a second elbow 16 fitted in the top of the float chamber 4 and having open communication therewith. It will thus be seen 45 that through these various passages the mixing chamber 6 has continuous and uninterrupted communication with the top of the float chamber 4 above the liquid fuel therein. Consequently the suction developed by 50 the pistons of the engine cylinders in descending on the intake strokes will operate to draw the air through the conduit 15 from the upper part of the float chamber 4, thereby creating a partial vacuum therein.

55 It is desirable that this partial vacuum in the float chamber 4 be kept substantially uniform, for this purpose air from the atmosphere may be admitted to the openings 9 in the cover 8 to meet the increased suction demands of the engine when running at high speed. This ingress of air from the atmosphere is advantageously under the control of a circular register valve 17 having a series of ports 18 extending substantially 60 in position and shape corresponding to the

openings 9 in the cover 8, in order to register completely therewith when the engine is running at maximum speed and thereby relieve the increased suction demanded thereby.

This valve 17 is mounted for rotation on the boss 13 and is subject to control in moving to mask or partially mask the openings 9 in the cover plate. The operation of this valve 17 is advantageously accomplished from the throttle control by a loose connection. The throttle valve is indicated at 19 as being on a stem 20 having the usual operating arm 21 connected up to the throttle control lever on the steering column. To the opposite end of the stem 20 is connected an arm 22 having a head 23 carrying lugs 24 and 25. These lugs project in the path of a second companion arm 26, which is connected to the valve 17 and through which said valve is shifted. The arm 26 is preferably 85 formed with a curved indentation entered by the lug 25 for purposes of smooth operation and yielding the required loose joint. The outlet of the carburetor, communicating with the manifold of the engine, is indicated at 28. 90

A brief description of the operation will serve to make clear the functioning of the various parts.

As indicated in the drawings, when the throttle valve 19 is closed the loose connection therebetween and the valve 17 will serve to shift the openings 9 and the ports 18 completely or almost completely out of registry so that no appreciable air from the outside atmosphere will be admitted to relieve the suction produced by the engine cylinders, but this engine suction will be entirely taken up by whatever air may be present in the upper part of the float chamber 4; which air will be delivered to the engine through the 105 conduit 15 and thereby leave a partial vacuum above the fuel in said float chamber 4. When the float device in the chamber 4 operates to open the valve, the partial vacuum in the float chamber will relieve the upper 110 surface of the fuel from appreciable pressure, while the atmospheric pressure on the upper surface of the fuel in the main fuel tank 2 will be operative to drive sufficient fuel from said main tank through the connection 3 and into the float chamber 4 to replenish the same to the constant level maintained therein by the float device. 115

After this constant level has been attained, the float will rise in the usual manner and close the float valve. At each successive falling of the fuel level in the chamber 4 this operation will be repeated, and the differences in pressure in the main tank 2 and float chamber 4 will be the means of 125 supplying the latter with the requisite quantity of fuel despite the difference in elevation of the two containers.

It will be evident that as the engine increases in speed so will the suction become 130

greater, and if not relieved will entirely devolve upon the float chamber 4. Too high degree of vacuum in the chamber 4 might interfere with the proper functioning of the 5 float device, and it is therefore desirable to keep the same substantially constant; this being done by admitting air from the outside atmosphere which will take up the increased pressure as the engine advances in 10 speed. Accordingly, as the throttle valve 19 is opened wider, the arm 22 will be correspondingly moved, and through the lugs 24 and 25 will shift the arm 26 and valve 17. By thus moving the valve 17 the openings 9 and ports 18 may be opened and closed, and a greater or less amount of air admitted in accordance with the speed of 15 the engine.

It will be seen that by the present arrangement all necessity of a separate vacuum tank is dispensed with, and the use of any more parts than the usual carbureter, excepting the small connection made by the present invention, are rendered entirely unnecessary.

It is obvious that those skilled in the art may vary the details of construction and arrangement of parts without departing from the spirit of my invention, and therefore I do not wish to be limited to such features except as may be required by the 30 claims.

I claim—

1. A carbureter having an air inlet and a 35 fuel-receiving chamber, a cover for said air

inlet having a radial series of ports, a mouth projecting inwardly from said cover and centrally with respect to said series of ports, a connection between said fuel-receiving chamber and mouth, a valve having a series 40 of ports adapted to register with the ports in said cover, and means to actuate said valve, substantially as described.

2. A carbureter having a fuel-receiving chamber and an air inlet, a cover for said 45 air inlet having a central aperture and a concentric series of ports, means for removably holding said cover in place, a flaring mouth projecting inwardly of said cover and in line with said aperture, a connection 50 between said aperture and fuel chamber, and a rotary valve having a concentric series of ports adapted to register with the ports in said cover, substantially as de- 55 scribed.

3. A carbureter having a fuel chamber and an air inlet, a cover having ports therein secured over said air inlet, a valve having ports adapted to register with said first-mentioned ports, a connection between said 60 chamber and cover to withdraw the air from the former, an arm on said valve, a second arm actuated from the throttle mechanism, and flanges on said second arm engaging said first-named arm, substantially as de- 65 scribed.

In testimony whereof, I affix my signature.

FREDERICK L. McCULLOCH.
